INVENTOR

UNITED STATES PATENT OFFICE

98,391

DESIGN FOR A GLOVE

Jerome J. Fox, New York, N. Y.

Application November 5, 1935, Serial No. 59,388

Term of patent 3½ years

To all whom it may concern:

Be it known that I, Jerome J. Fox, a citizen of the United States of America, residing in Manhattan, county of New York, and State of New York, have invented a new, original, and ornamental Design for a Glove, of which the following is a specification, reference being had to the accompanying drawing, forming part thereof, wherein,

Figure 1 is a front view of a glove showing my new design.

Figure 2 is a rear view of the glove shown in Figure 1.

The characteristic feature of the present invention lies in the provision of a comparatively heavy cord mounted upon a sewed border at the wrist portion of the glove, the cord having its free ends tied and each end being provided with a ball shaped end as shown.

I claim:

The ornamental design for a glove, substantially as shown and described.

JEROME J. FOX.
